UNITED STATES PATENT OFFICE.

PAUL H. LOGAN, OF EL PASO, TEXAS, ASSIGNOR OF ONE-HALF TO PRESTON E. GARDNER,
OF EL PASO, TEXAS.

DEVICE FOR PREVENTING OVERFLOW OF TANKS.

Specification of Letters Patent.

Patented Apr. 4, 1916.

1,177,956.

Application filed February 16, 1915. Serial No. 8,607.

To all whom it may concern:

Be it known that I, PAUL H. LOGAN, a citizen of the United States, residing at El Paso, in the county of El Paso and State of Texas, have invented a new and useful 5 Device for Preventing Overflow of Tanks, of which the following is a specification.

The device forming the subject matter of this application is adapted to be employed 10 for preventing the repeated discharge of the contents of a flush tank, should the float controlled valve in the supply pipe for the flush tank prove inoperative for any reason.

The invention aims to provide a novel device, actuated by the contents of the flush tank, for closing a valve in the supply pipe when the contents of the flush tank rises above a predetermined level.

It is within the scope of the disclosure to 20 improve generally and to enhance the utility of devices of that type to which the present invention appertains.

With the above and other objects in view which will appear as the description proceeds, the invention resides in the combination and arrangement of parts and in the details of construction hereinafter described and claimed. Changes can be made within the scope of what is claimed without departing 30 from the spirit of the invention.

In the accompanying drawing:—Figure 1 is a sectional view in which sundry parts appear in elevation, portions being broken away; Fig. 2 is a top plan of the movable receptacle which actuates the valve in the pipe; Fig. 3 is a longitudinal sectional view of the movably mounted receptacle, the connection between the receptacle and the valve in the supply pipe appearing in elevation.

40 In the accompanying drawings, the numeral 1 indicates a receptacle of any sort such as a water closet bowl.

The numeral 2 indicates a flush tank supported in any manner as indicated at 3. The 45 discharge or flush pipe which leads from the tank 2 to the water closet bowl 1 or other receptacle is denoted by the numeral 4. The numeral 5 indicates a vertically movable siphon coacting with the upper end of the flush pipe 4, the siphon 5 being controlled by means of a lever 6 fulcrumed intermediate its ends on a support 7 and ordinarily actuated by means of a flexible element 8.

55 A supply pipe 9 communicates with the

tank 2 and at the upper end of the pipe 9 there is a valve 10 controlled by a lever 11 actuated by a float 12.

The foregoing structural details are common and well known in the art, and no 60 novelty is claimed for them, saving in so far as they may coöperate with sundry parts to be described in detail hereinafter.

If from any cause, the valve 10 which controls the supply pipe 9 becomes inoperative, 65 the water rises in the tank 2 to the crown of the siphon 5, and thereupon the contents of the tank are discharged through the pipe 4, this operation continuing repeatedly, with obvious waste. The continued discharge 70 through the supply pipe 9 into the tank 2 may take place when there is an unduly heavy pressure in the pipe 9, if the float 12 becomes detached from the lever 11, if the lever 11 becomes accidentally detached 75 from the valve 10, and from other causes comprehended by those skilled in the art. In view of the foregoing, it will now be understood that the object of the present invention is to prevent a repeated discharge 80 of the contents of the tank 2 under the circumstances above pointed out.

In the present embodiment of the invention, vertically spaced brackets 14 are attached to one end of the flush tank 2, the 85 brackets 14 being connected by upright guides 15, the brackets and the elements 15 coacting to form a guiding structure in which is mounted to reciprocate a receptacle 17. The receptacle 17 is entirely closed, 90 saving for a pet cock 19 in the bottom of the receptacle, and a gland 18 in the top of the receptacle which receives the depending portion of an angular pipe 16, the pipe 16 entering the tank 2 slightly below the crown 95 of the siphon 5. The receptacle 17 is mounted to reciprocate in the guides 15 and upon the depending end of the pipe 16. The receptacle 17 is provided with a depending ear 20 to which is pivoted as shown at 20°, the 100 upper end of a longitudinally extensible connection which may be a turnbuckle 21, the lower end of the turn buckle being pivoted as shown at 21° to a slide 22 mounted to reciprocate for adjustment in a tubular stem 23 105 forming a part of a valve 24 interposed in the supply pipe 9, the slide 22 and the stem 23 forming a longitudinally extensible lever whereby the valve 24 is controlled. This longitudinally extensible lever may be held 110

at adjusted lengths by means of a set screw 25 threaded into the stem 23 and engaging the slide 22.

If through any of the causes hereinbefore mentioned, the water rises to an undue level within the flush tank 2, the water will flow by way of the pipe 16 into the receptacle 17 and the latter will be depressed, the bottom of the receptacle 17 moving away from the lower end of the pipe 16, and the air in the receptacle bubbling away through the pipe 16. When the receptacle 17 descends, the valve 24 will be actuated through the medium of the lever 23-19 and the connection 21, the valve being moved to a closed position, so as to cut off the supply pipe 9. Thereupon, no more water will enter the flush tank 2 by way of the pipe 9 and a repeated siphoning out of the flush tank 2, with consequent waste, will be avoided. In order to reset the structure, the pet cock 19 is opened and the receptacle 17 is drained, whereupon the receptacle may be elevated to the position shown in Fig. 1, the valve 24 ordinarily operating with sufficient friction to hold the receptacle in its raised position. Obviously, by means of the slide 22 and the stem 23, together with the longitudinally extensible turn buckle connection 21, the throw of the valve 24 may be regulated, and at the same time, the closing of the valve 24 when the receptacle 17 is depressed may be assured.

Having thus described the invention, what is claimed is:

1. In a device of the class described, a tank; an outlet for the tank; means for controlling the outlet; a supply pipe for the tank; a movable receptacle located exteriorly

of the tank; means for conducting the contents of the tank into the receptacle after the contents of the tank has risen to a predetermined level; a valve in the supply pipe; and an operative connection between the receptacle and the valve and disposed exteriorly of the tank.

2. In a device of the class described, a tank; an outlet for the tank; means for controlling the outlet; a supply pipe for the tank; a conduit leading from the tank; a receptacle mounted to slide upon the conduit and adapted to receive the contents of the tank through the conduit; a valve in the supply pipe; and a connection between the receptacle and the valve.

3. In a device of the class described, a tank; an outlet for the tank; a vertically movable siphon controlling the outlet; means for operating the siphon; a supply pipe for the tank; a valve in the supply pipe; float controlled means for operating the valve; a guiding structure carried by the tank; a receptacle mounted to reciprocate in the guiding structure; an angular pipe, one end of which enters the receptacle, the other end of which enters the tank; a second valve in the supply pipe; a longitudinally extensible lever united with the valve; and a longitudinally extensible connection uniting the lever with the receptacle.

In testimony that I claim the foregoing as my own, I have hereto affixed my signature in the presence of two witnesses.

PAUL H. LOGAN.
